UNITED STATES PATENT OFFICE.

HARRY M. HAMRICK AND WILLIAM S. MILLER, OF PHILADELPHIA,
PENNSYLVANIA.

BURNER.

SPECIFICATION forming part of Letters Patent No. 613,649, dated November 1, 1898.

Application filed June 21, 1898. Serial No. 684,065. (No model.)

To all whom it may concern:

Be it known that we, HARRY M. HAMRICK and WILLIAM S. MILLER, citizens of the United States, residing in the city and county 5 of Philadelphia, State of Pennsylvania, have invented a new and useful Improvement in Burners, which improvement is fully set forth in the following specification and accompanying drawings.

Our invention relates to an improved construction of burner for illuminating purposes; and the object is to provide a burner of this character wherein the gasolene or other liquid illuminant will be converted into a gas or vapor after having left its source of supply prior to or at about the time of its admission into the burner, means being provided for controlling the supply to said burner and for retaining a large proportion of the heat within the burner in order that a superior gas may be generated therein and a more perfect combustion thereof result.

It also consists of a suitably-supported mantle suspended above and adjacent to the mouth of the burner, whereby the flame as it emanates from the burner and surrounds the mantle will be spread or deflected, so as to increase the illuminating power thereof, and whereby also the heat units which are contained in said mantle may be returned to the burner, and thus intensify the heat thereof to a maximum degree.

It also consists of a burner comprising a shell or tube, a gas-generating chamber located at one end thereof, and a perforated diaphragm located within said tube and intermediate of its ends, means for supplying said gas-generating chamber with gasolene or other liquid illuminant and for controlling the supply thereof to said burner, and means for retaining and intensifying to a maximum degree the heat in said burner when in operation.

It further consists of novel details of construction, all as will be hereinafter fully set forth, and particularly pointed out in the claims.

Figure 1 represents a side elevation of a burner embodying our invention. Fig. 2 represents a longitudinal section of the same, showing also the preferred arrangement for

supplying said burner with the gasolene or other illuminant. Fig. 3 represents an inverted plan view, on an enlarged scale, of a ring to which the mantle is secured and which 55 forms a support therefor. Fig. 4 represents a longitudinal section of the mantle and its adjuncts. Fig. 5 represents a side elevation of the supporting-ring for the mantle in detached position. Fig. 6 represents a longitudinal section of a slightly-modified construction of our invention. Fig. 7 represents a side elevation of the same, the burner being shown in this instance as provided with an asbestos or other refractory cover. 60 65

Similar letters of reference indicate corresponding parts in the figures.

Referring to the drawings, A designates the burner, the same consisting of a shell or a tube B, having a series of perforations C 70 near its lower extremity for the admission of air and a series of perforations D near its upper extremity through which a portion of the flame escapes when the burner is in operation.

E designates the threaded neck or extension of a casing F, to which the lower internally-threaded extremity of the shell or tube B is secured, the said casing being provided with a chamber G, the latter having a port H leading therefrom into the shell or tube B and through which the gas generated within the chamber G escapes into the burner. The lower end of the casing is provided with a threaded opening adapted to receive the 80 85 threaded stem K of a needle or similar valve L, which serves to control the supply of gas to the burner, although it is evident that under certain conditions we may dispense with said valve and reduce the size of the port H in 90 order that a predetermined and continuous supply of illuminant may be introduced to the burner.

M designates a supply-pipe which may lead from any convenient source of supply, (not 95 shown,) and the gasolene or other liquid illuminant may be forced or allowed to pass into the chamber G through said pipe, it being observed that the pipe M in Fig. 1 leads directly to the chamber G, while in Fig. 2 it is 100 coiled around the burner A before entering said chamber, the latter arrangement being

intended to heat the gasolene to a higher degree as it passes through the coil and so facilitate and accelerate the production of the gas.

- 5 The interior of the burner A is provided with a perforated or gauze diaphragm P, the same being located slightly below the level of the perforations D, so that as the gases rise within the shell B and commingle with the 10 air drawn in through the perforations C their ascent will be retarded by said diaphragm and a perfect combustion at that point will ensue, the flame being contained within the said shell or casing between its upper extremity and the diaphragm will radiate through and heat the burner, and any flame which may pass out through the perforations D will give additional heat to the exterior of the 15 burner, as will be evident.
- 20 Q designates a frame, the same consisting of an arm or standard T, having its lower extremity attached to a collar R, the latter being formed with an annular top flange S, adapted to rest upon the upper extremity of the shell or casing B, the lower edge of said collar terminating above the perforations D.
- 25 The upper extremity of the arm Q is provided with a laterally-extending support U, which may be arranged in substantial alignment with the collar R and upon which pins V of a ring W rest, the latter being secured to and forming part of an inverted conical mantle A', the action of which is similar to that of a Welsbach mantle.
- 30 The ring W is formed with an annular groove X and an adjacent flange Y, having radial recesses Z, in which the ends of a plurality of strands of wire are inserted, the same being secured therein by means of a wire B' 35 or other suitable fastening, fitting into the groove X and binding the ends of said strands, the lower extremities thereof being fastened to the converging ends of wires C', whereby a substantial and effective mantle is secured.
- 40 Referring now to Figs. 6 and 7, B^X designates a shell or tube similar to that hereinbefore described; but in this construction the lower perforations C are omitted, and in their stead a space C^X is left between the lower extremity of the shell or tube and a casing F^X for the admission of air into the burner A, to which latter the supply-pipe M^X is brazed or otherwise secured. The casing F^X is provided with a port or orifice G^X, adapted to receive 45 therein the lower extremity of the supply-pipe M^X, which latter leads to the gas-generating chamber G, as shown, and in this manner a convenient and substantial support is provided for the valve-casing, as will be evident.
- 50 N^X designates a cover or casing, which may be composed of asbestos or other refractory material, the same being provided with perforations P^X at or near the lower extremity 55 thereof for the admission of air to the burner, the said cover being designed to inclose the burner in such manner that while serving to

retain and intensify the heat therein it will in no wise interfere with the free circulation of the air, which may pass up from below the cover and through the perforations P^X therein, as described. This cover may be applied to any of the forms of burners herein shown and described and is particularly advantageous in winter time or under conditions where a low temperature prevails.

It will be understood, of course, that the valves for controlling the supply of gasolene or other liquid illuminant to the burner and the mantle and other parts or adjuncts specifically described as pertaining to Figs. 1 to 5, inclusive, and not referred to in connection with Figs. 6 and 7 will be used therewith in substantially the same form.

It has been found in practice that the best results are obtained by making the ring W of copper, as well as the support U, the standard Q, and the collar R, the mantle A' being preferably made of platinum or similar material.

Having thus described our invention, what we claim as new, and desire to secure by Letters Patent, is—

1. A burner consisting of a tube, a series of perforations located in the upper portion of said tube, a gauze located below said perforations, a chamber for the reception of the hydrocarbon, means for enabling said burner to generate its own gas by its own heat and a mantle suitably supported above said tube.

2. A burner consisting of a tube, a series of perforations in the upper portion thereof, a gauze located below said openings, other openings in the lower portion of said tube, a collar supported upon the latter, a standard arising from said collar, a laterally-extending member attached to said standard, a ring supported upon said member, and a mantle depending from said ring.

3. In a burner, a tube, having perforations at the upper and lower portions thereof, gauze located transversely in said tube below the upper series of perforations, a chamber having a needle-valve therein, secured to the lower portion of said tube, a collar supported upon the upper portion of said tube, the lower edge of said collar terminating above the upper series of perforations in said tube, a standard arising from said collar and a mantle supported from said standard.

4. A mantle consisting of a ring having projections extending therefrom, an annular groove in said ring below said projections, whereby a lower projecting flange is formed, a plurality of recesses or cuts in said lower flange, a series of wires having their upper ends seated in said recesses, said ends being bent into said groove, and a rod seated in the latter, the lower ends of said wires converging and being suitably secured together in assembled position.

5. A burner consisting of a tube, a series of perforations in the upper portion thereof, a gauze located below said perforations, a

- standard supported upon said tube, said standard having a laterally-extending member, a mantle supported upon said member, and means for enabling said burner to generate its own gas by its own heat, in combination with a casing or covering of suitable non-conducting material, said casing inclosing said burner. 5
6. A burner, consisting of a tube, a chamber for the reception of the hydrocarbon, openings in said tube, a standard supported upon the latter, a mantle suitably supported above said tube, and a pipe leading to said chamber and coiled about said tube, said burner being adapted to generate its own gas by its own heat. 5
7. A burner consisting of a tube having perforations in the upper and lower portions thereof, gauze located transversely in said tube below the upper perforations, a collar supported upon the upper end of said tube and having an inwardly-extending flange whereby said collar is held in position, a standard arising from said collar, a ring having a mantle projecting therefrom, and supporting devices common to said ring and standard. 5
8. In a burner, a tube, having perforations therein, a chamber for the reception of the hydrocarbon, means for enabling the burner to generate its own gas by its own heat and a standard sustained upon said tube, in combination with a mantle supported from said standard, said mantle consisting of a ring having a groove therein, whereby a lower flange is formed, recesses in said flange, wires having their upper ends seated in said recesses and deflected into said groove and a fastening device seated in the latter, the lower ends of said wires converged, and means for securing said lower ends in assembled position. 5
9. A burner consisting of a tube, a chamber for the reception of the hydrocarbon at the lower portion thereof, openings located at the upper and lower portions of said tube, a mantle suitably supported above said tube, a gauze in said tube adjacent the outlet thereof, and a pipe leading to said chamber and coiled about said tube, said burner being adapted to generate its own gas by its own heat. 15
10. A burner, consisting of a tube having openings in the upper and lower portions thereof, a gauze supported below said upper openings, a collar supported upon the upper end of said tube, and having an inwardly-ex- 10
- tending flange engaging said tube, a standard 55 arising from said collar and having a laterally-projecting member, a ring having a mantle depending therefrom, supporting devices common to said ring and to said laterally-extending member, a chamber for the reception of 60 the hydrocarbon, means for enabling said burner to generate its own gas by its own heat, and a suitable non-conducting casing or covering inclosing said burner. 65
11. In a burner, a tube, a series of perforations in the upper portion thereof, a gauze located below said openings, and a chamber for the reception of the hydrocarbon, means for causing the burner to generate its own gas by its own heat, and a standard supported 70 upon said tube, in combination with a mantle supported from said standard, said mantle consisting of a ring and a plurality of wires secured thereto, the lower ends of said wires being converging. 75
12. A mantle consisting of a ring having a groove therein whereby a lower projecting flange is formed, a plurality of recesses or cuts in said flange, a series of wires having their upper ends seated in said recesses and 80 deflected into said groove, a fastening device seated in the latter, the lower ends of said wires converged, and means for securing said lower ends in assembled position. 85
13. A burner consisting of a tube, a series of perforations located in the upper portion of said tube, a gauze located below said perforations, a chamber for the reception of the hydrocarbon, means for enabling said burner to generate its own gas by its own heat and a 90 mantle suitably supported above said tube, in combination with a non-conducting covering for said burner. 95
14. A burner consisting of a tube, a chamber for the reception of the hydrocarbon, a series of perforations in the upper portion of said tube, a gauze located below said perforations so that a portion of the flame is forced through said openings and assists in heating the tube, the latter serving as a conductor of 100 heat to said chamber and a mantle suitably supported above said tube. 100
